DISPLAY SIGN

Richard E. Fox, Glenview, Ill., assignor to General
Porcelain Enameling and Manufacturing Com-
pany, Chicago, Ill., a corporation of Illinois

Application July 10, 1950, Serial No. 172,920

3 Claims. (Cl. 40—143)

1

My invention relates to a display sign, and more particularly to a sign wherein members containing word forming letters or other insignia are mounted on a background panel in a semi-permanent manner.

The invention likely will find its greatest use in connection with store fronts covered with porcelain enamel panels, and in most instances, the individual letter or sign members themselves likewise will be made of porcelain enamel metal. However, the invention in its broadest aspects is not limited to the use of this particular material.

One object of the invention is to provide a display sign wherein the individual sign members in the sign are semi-permanently associated with a background forming support. The members are mounted in such a way that they are not readily removable, but, on the other hand, they rather easily can be removed and replaced with other letters when desired.

Another object is to provide a display sign that possesses highly desirable aesthetic qualities and has striking attention-compelling characteristics.

Another object is to provide a display sign of this character that can be made of sheet metal material and be finished with porcelain enamel. The use of a porcelain enamel finish has imposed stringent limitations upon constructions of this type because of the high temperatures required during the oven firing process. Unless certain techniques are followed, such as are described in detail hereinafter, the individual sign members are subject to objectionable warping as a result of the high temperatures. Also, unless certain precautions are followed, the porcelain enamel is likely to crack and chip upon installation of the sign members. Certain procedures forming part of my invention effectively eliminate the aforesaid shortcomings encountered due to the use of porcelain enamel.

Other objects and advantages of the invention will be apparent as the description proceeds, reference being had to the accompanying drawing which illustrates one structural form of the invention. It is to be understood, of course, that in commercial applications of the invention various details might well vary somewhat from those here shown and described.

In the drawing:

Fig. 1 is a front elevational view of a display sign embodying my invention showing three sign members mounted on a background panel;

Fig. 2 is a top view thereof;

Fig. 3 is an end elevational view thereof;

Fig. 4 is a sectional view on line 4—4 of Fig. 1;

2

Fig. 5 is a sectional view on line 5—5 of Fig. 1; Fig. 6 is a fragmentary view, partly in section, illustrating a detail of the invention, and

Fig. 7 illustrates the shape of a partially formed sign member.

Referring to the drawing, my improved display sign comprises a background and supporting panel 10 that is made of stiff sheet material. If a porcelain enamel finish is contemplated, the sheet material used should be metal, preferably of about 18 gauge. A panel of this thickness, when provided with the presently to be described marginal flanges, does not warp appreciably during the firing process.

Panel 10 in the usual case is generally rectangular in shape, and it is adapted to be mounted in a vertical plane with the narrow dimension extending vertically. The upper marginal portion of panel 10 is bent forwardly out of the plane of the panel at an angle less than 90°, preferably approximately 30°, to provide an upwardly inclined flange 11. The free edge of flange 11 may be bent back upon itself for reinforcement as shown in Figs. 3 and 4. Panel 10 also preferably has lateral flanges 12 for the purpose of reinforcement and to provide proper juncture with horizontally adjacent panels. The lower marginal portion of panel 10 is bent to provide a flange 13 along the bottom of the panel. Flange 13 preferably is generally arcuate in shape, and, as later described, the flange forms one element of a spring actuated lock.

Panel 10 is provided with suitable means such as slots 15 (Figs. 3 and 4) for mounting the panel in position on a vertical surface, such as the front wall of a building. Slots 15 fit over horizontal members (not shown) carried by the building wall.

Adapted to be mounted in a semi-permanent manner on a panel 10 are a plurality of sign members 18, three of which are shown in Figs. 1 and 2. Sign members 18 are adapted to be imprinted with letters or other desired insignia, the letters P E P being shown by way of illustration.

Each sign member 18 comprises a display face 20 which, when the member is mounted on a panel, is disposed in a plane parallel to and forwardly of the panel, as clearly shown in the drawing. A letter or other insignia is applied to display face 20, and, if the member is finished with porcelain enamel, the various enamel coatings should be applied in a manner hereinafter described.

The sign member is made of relatively stiff sheet material, preferably 16 gauge metal if porcelain enamel is to be used. Lateral flanges 21

and top and bottom flanges 22 extend rearwardly from display face 20. Sign member 18 has means for mounting the member to supporting panel 10, which means may take the form of aligned, inclined notches in lateral flanges 21 which receive inclined flange 11 of the panel.

In order to lock sign member 18 to panel 10 in a semi-permanent manner, bottom flange 22 terminates in a shaped portion 24 that forms a second element of the aforesaid spring actuated lock. The vertical dimensions of panel 10 and sign member 18 are such that shaped portion 24 of flange 22 makes a close fit with lower flange 13 of the panel. In fact, bottom flange 22 of the sign member must be resiliently distorted in order to establish the proper relation between its shaped portion 24 and the panel flange 13. The resilient characteristic of the material in sign member 18 insures a spring lock relationship between the member and panel 10. With metal having the stiffness of 16 gauge steel, it will be understood that considerable force must be applied to achieve the distortion necessary for mounting or demounting the sign member.

Upper flange 11 of panel 10, in addition to performing its primary function of supporting the sign members, also functions as a shield to prevent rainwater and the like from flowing down over the surface of background panel 10. This materially reduces the maintenance necessary for proper appearance of the sign.

The general appearance of my display sign is enhanced if lateral flange 21 and top and bottom flanges 22 of the sign member are inclined with respect to display face 20. In the illustrated form of the invention, lateral flanges 21 are parallel with each other, and they extend at an acute angle, about 45°, with the plane of display face 20. Similarly, top and bottom flanges 22 are parallel with each other, and they extend at a like acute angle with the plane of the display face.

Fig. 7 shows an intermediate stage in the production of a sign member having inclined flanges. This stage follows use of a suitable die for stamping blanks of the shape shown in the figure. In case a porcelain enamel finish is to be employed, the ends of flanges 21 and 22 are so cut that when the flanges are bent to their final, inclined state, there will be appreciable spaces between adjacent panel ends. Also, the flanges are cut away slightly in the region of the corners of display face 20, as shown at 23. This spacing between the adjacent ends of the flanges and the additional spacing at the corners have been found necessary to the proper application of porcelain enamel to the sign member, as will be later described.

A small hole 28 is made in the righthand flange 21, looking at Fig. 7, this flange being the lateral flange that ultimately is bent under display face 20. Thus hole 28 will not normally be visible in the finished sign. Hole 28 receives a hook that supports the sign member during oven firing of the porcelain enamel finish. It has been found that hole 28 should be located generally as illustrated in order to minimize undesirable warping during the firing process.

After preparing the blanks illustrated in Fig. 7, suitable dies are used to bend the flanges into final, inclined position, leaving the aforementioned spacing between the flange ends. Thereafter, the sign members may be finished with the desired paint or porcelain enamel, and letters or insignia are applied thereto.

When porcelain enamel is used, the previously

formed sign member is carefully cleaned so that it is properly conditioned for application of the enamel. The usual ground coat is applied to all surfaces of the sign member. This is most easily accomplished by a dipping process. The appreciable spaces left between the flange ends and the enlarged spaces at the corners prevent the enamel of the ground coat from bridging or covering the junctures of the flanges. If such bridging were permitted the porcelain enamel would tend to crack or chip in the region of the flange ends. After dipping, the ground coat is oven fired in the usual manner.

The color of the ground coat is usually black or dark blue, and this color is highly satisfactory for one of the contrasting colors normally used on the sign members.

In one highly satisfactory manner of finishing the sign members, display face 20 is given a second coat of porcelain enamel that contrasts strikingly with the ground coat. This second coat may be white. It is normally applied by means of a screen stencil to display face 20, after which the sign member is again fired. The size of the stencil opening should be so chosen that the second coat terminates short of the edges of display face 20. This is for the reason that a second coat is much more susceptible to cracking and chipping than the first coat when the underlying metal is appreciably distorted. Such distortion occurs at the juncture of bottom flange 22 and display face 20 when the sign member is mounted or demounted.

Display letters or other insignia are thereafter applied to the display surfaces of the sign members. In a particularly effective sign wherein the ground coat is black and the second coat on display face 20 is white, the color red is used for the letters or insignia. Here again a screening process is used to properly apply the porcelain enamel to the sign member, after which the sign member is again fired.

In all instances of firing the sign member is supported in the oven by a hook passing through hole 28 in lateral flange 21. As mentioned, the location of this hole is important from the standpoint of minimizing objectionable warping.

The finished sign member 18, it will be noted, is extremely economical to produce. It involves a single stamping operation for the preparation of the blank shown in Fig. 7. Thereafter, the flanges are bent by means of a succession of simple die operations. There is no expensive welding, since the thickness of the sheet material is sufficient to insure proper rigidity of the sign members. Furthermore, welding would inherently result in objectionable warping.

Mounting and demounting of sign member 18 is easily accomplished by merely flexing bottom flange 22. Because of the rigidity of the sheet material of which the sign member is made, considerable force is required to bring about the flexing necessary to mount or demount the member. This is adequate insurance against unauthorized removal of the sign members.

From the above description it is thought that the construction and advantages of my invention will be readily apparent to those skilled in the art. Various changes in detail may be made without departing from the spirit or losing the advantages of the invention.

Having thus described my invention, what I claim as new and desire to secure by Letters Patent is:

1. A display sign comprising a generally rec-

tangular panel of stiff sheet material adapted to be mounted in a vertical plane, said panel having the upper marginal portion thereof bent forwardly out of the plane of the panel at approximately 30° to provide an upwardly inclined flange and the lower marginal portion thereof bent rearwardly to provide a flange of generally arcuate shape, and a sign member of relatively stiff sheet material adapted to be mounted on said panel, said sign member having a display face disposed in a plane parallel to said panel and forwardly thereof, lateral and top and bottom flanges extending rearwardly of said display face, said lateral flanges having aligned inclined notches therein adapted to receive the inclined flange of said panel to thereby support said sign member, said bottom flange terminating in an arcuate shape whereby to interfit in a spring pressed manner with the arcuate flange of said panel and lock said sign member to said panel. 20

2. The combination of claim 1 wherein the lat-

eral flanges of said sign member are parallel with each other and extend at an acute angle with the plane of said display face, and wherein the top and bottom flanges of said sign member likewise are parallel with each other and extend at an acute angle with the plane of said display face.

3. The combination of claim 1 wherein said sign member is made of sheet metal and is finished with porcelain enamel, and wherein the flanges thereof have end portions spaced appreciably from the end portions of adjacent flanges to avoid having the porcelain enamel cover the juncture of adjacent flanges.
